FOUNTAIN PEN WITH VALVE NORMALLY CLOSING THE AIR-AND-INK TUBE

Filed April 26, 1954

2 Sheets-Sheet 2

Inventor:
Benjamin F. Miessner.

BY *A. D. T. Libby*
Attorney.

23 and 24 are larger than the diameter of the member so as to allow the member 5 to expand as shown in Figure 4 and open the valve member 5. The hole in member 20 is also the same size as holes in 23 and 24 for the same purpose. Then the finger 21 and the link 25 are brazed or spot welded to the spring ring 14 the same as the U-shaped wires 15, 18 and 19. While two different means are illustrated for cooperation with the valve member 5 the operation of the two are identical with respect to opening and closing of the valve, it being understood that the opening is done manually but it closes automatically when pressure is released from the spring ring 14. An auxiliary but important function of the valve members 15 and 18-19 is to prevent over squeezing of the barrel 1, since the inner, opposite sides of band 14 act as stops for the free ends of members 15, 18 and 19.

With respect to the pen point P a thin narrow strip 26 of spring metal of suitable non-corrosive material is spot welded at 27 to the pen point. In the outer end of the strip 26 is fastened as by welding a blade 28 preferably made of a platinum-iridium alloy or other hard, ink-wettable metal which is noncorrosive. This blade is very thin, of the order of approximately .005". Its edge is sharp and is always positioned in the slit 29 between the pen nibs. The inner edge 30 is rounded longitudinally as well as transversely so that when pressure is applied to the pen nibs the upper edge will move between the nibs and clean out any obstructing material therein, and still allow ink to flow down to the free ends of the nibs. Furthermore, this construction automatically allows a heavier line to be made by a very slight tilting of the pen point, the nibs of which will be moved according to the surface 30.

The reservoir 1 of this pen is filled by immersion of the pen point end in a container of ink, and at the same time, squeezing the barrel 1 across the valve member, as illustrated in Figure 4, to expell air. This opens the valve and, as the squeezing pressure is released, ink flows up through tube 4, open valve tube 5, and tube 3, into barrel 1. A series of 5 or 6 such operations will completely fill barrel 1.

In the pen assemblies as described it will be readily understood that, when ink is passed through the tube sections 3 and 4 with the valve 5 opened for re-filling the collector as defined by the tubes, ink will pass out of the oval opening 8 and downwardly through the spaces between tubes 4 and 10, looking at Figure 1, and through the holes 11 and 11' and up within the space between the tubes 10 and 10', and also up between the tube 10' and the bore in the hood, and up to the pen shank, and through the hole 13 therein to the larger bore around the outer part of the pen shank. This new arrangement of spaced co-axial tubes provides a generous supply of ink to the pen nibs in a new and novel manner, whereby the objects of the invention are attained, especially the principal object thereof.

Having thus described my invention, what I claim is:

1. A fountain pen having a hood carrying a pen point and a barrel type air and ink reservoir joined to the hood, the hood also acting as the main support for an air and ink tube divided into two sections, for carrying air and ink to the pen point, a flexible member of suitable material forming a valve union member between said two sections, and means normally pressing against said flexible member to maintain the valve shut, said means being responsive to pressure applied to the barrel diametrically across the central part of said union member, to allow said member to assume a valve open position.

2. A fountain pen as set forth in claim 1 further defined in that said means includes a band of relatively thin metal of suitable material positioned against the inner wall of the barrel, and at least a pair of curvilinearly shaped members disposed diametrically one on each side of the said union member and each having extending parts fastened to said ring as and for the purpose described.

3. A fountain pen as set forth in claim 1 further defined in that said means includes a band of relatively thin metal of suitable material positioned against the inner wall of the barrel, a U-shaped member freely encompassing the valve union member and having its arm ends fastened to said ring and at least one other U-shaped member freely encompassing said valve member adjacent the first U-shaped member but extending diametrically in an opposite direction and with its arm ends fastened to said ring for the purpose described.

4. A fountain pen as set forth in claim 1 further defined in that said means includes a ring of relatively thin metal of suitable material positioned against the inner wall of the barrel, a U-shaped member freely encompassing the valve union member and having its arm ends fastened to said ring and a pair of U-shaped members freely encompassing said valve member, one on each side of the first-mentioned U-shaped member but extending diametrically in an opposite direction and having its arm ends fastened to said ring for the purpose described.

5. A fountain pen as set forth in claim 1 further defined in that said means includes a ring of relatively thin metal of suitable material positioned against the inner wall of the barrel and at least a pair of curvilinearly shaped members disposed diametrically one on each side of the said union member and each having extending parts fastened to said ring and further defined in that the curvilinearly shaped members are in wire form.

6. A fountain pen as set forth in claim 1 further defined in that said means includes a ring of relatively thin metal of suitable material positioned against the inner wall of the barrel and at least a pair of curvilinearly shaped members disposed diametrically one on each side of the said union member and each having extending parts fastened to said ring and further defined in that the curvilinearly shaped members are made from flat stock and have projections which are fastened as by welding to said ring.

7. A fountain pen having a hood carrying a pen point and barrel type reservoir fastened to the hood, the barrel being only transversely compressible, an air and ink tube divided in two sections joined in longitudinal spaced relation by a tube of suitable flexible material acting as a valve, the said air and ink tube extending from a point near the pen nibs to a point near the end of the barrel farthest from the hood, a relatively narrow metal ring of suitable springy material positioned against the inner wall of the barrel at a position opposite the longitudinal midsection of said flexible tube, a plurality of members having arcuate surfaces for freely engaging said flexible tube preferably at its midsection, said members having stiff arms extending to said ring and fastened thereto whereby due to normal pull on said arms by the said ring, the said members having the arcuate surfaces will be moved so as to grip the said flexible tube and move it into a closed position, said ring being actuatable by pressure on the barrel over the ring to remove the grip on the tube so it will automatically move to open position.

8. A fountain pen as set forth in claim 7 further defined in that said members having the arcuate surfaces for engaging the flexible valve tube are preferably arranged two on one side and one on the opposite side of the valve tube but positioned between the said two whereby the lateral side of the members act to keep themselves in operative alignment.

9. A fountain pen as set forth in claim 7 further defined in that said members having the arcuate surfaces for engaging the flexible valve tube are each in the form of a U with the ends of the arms of the U fastened to the said ring while the curved part of the U partially encircles the valve tube as and for the purpose described.

10. A fountain pen as set forth in claim 7 further defined in that said members having the arcuate surfaces for engaging the flexible valve tube are made from a piece of relatively thin flat metal of suitable material, the arcuate

surfaces defining holes which fit loosely over the valve tube while a stud extends from the outer surface of the material having the hole therein to said ring to which they are fastened as and for the purpose described.

11. A fountain pen having a hood and an interconnected air and ink barrel which is radially compressible but rigid longitudinally, an air and ink tube extending from the inner extremity of the barrel to a point near the pen nibs, the air and ink tube having two sections joined by a tubular flexible member and means carried 5 within the barrel and operatively connected between the barrel and said tubular flexible member, said means normally exerting a pressure on the flexible tubular member to completely close it, said means being responsive to pressure on the barrel at proper points to allow the flexible member to move to open position. 10 15
